[57] **CLAIM**

The ornamental design for a integrated car dubbing system, as shown.

DESCRIPTION

FIG. 1 is a front elevational view of the integrated car dubbing system of the present invention;

FIG. 2 is a back elevational view of the integrated car dubbing system of FIG. 1;

FIG. 3 is a left side elevational view of the integrated car dubbing system of FIG. 1.

FIG. 4 is a right side elevational view of the integrated car dubbing system of FIG. 1.

FIG. 5 is a top plan view of the integrated car dubbing system of FIG. 1.

FIG. 6 is a bottom plan view of the integrated car dubbing system of FIG. 1.

The broken line showing on FIG. 1 is for illustrative purposes only and is not a part of the claimed device.
